UNITED STATES PATENT OFFICE.

JOE SZCZUREK, OF CHICAGO HEIGHTS, ILLINOIS.

PIN-PROTECTOR.

1,356,668.

Specification of Letters Patent. Patented Oct. 26, 1920.

Application filed May 21, 1919. Serial No. 298,657.

To all whom it may concern:

Be it known that I, JOE SZCZUREK, a citizen of Poland, residing at Chicago Heights, county of Cook, and State of Illinois, have 5 invented certain new and useful Improvements in Pin-Protectors, of which the following is a specification.

This invention relates to improvements in devices for protecting the points of pins 10 such as are used in securing hats in adjusted position.

The principal object of the invention is to provide a device which will effectively engage with the pin points, preventing it from 15 being inadvertently removed, and also avoiding the danger of having the point of the pin make contact with adjacent persons or objects.

A still further object is to provide a pin 20 protector of highly ornamental appearance, and which may be operated effectively by the hand of the wearer, either with or without the use of a mirror.

These and other like objects are attained 25 by the novel construction and combination of parts hereinafter described and shown in the accompanying drawings, forming a material part of this disclosure, and in which—

Figure 1 is a side elevational view showing 30 a conventional type of pin and a protector made in accordance with the invention.

Fig. 2 is an enlarged vertical sectional view taken through the protector, and indicating its engagement with the pin point.

Fig. 3 is a transverse sectional view on line 3—3 of Fig. 2.

Referring to the drawings, the bar or shank of the pin is indicated by the numeral 10, the same having an ornamental head 11, 40 and a sharply conical point 12, as is common with pins of this description.

In the preferred form of protector, a pear shaped body 14 contains an axial bore 15, suited to receive the point 12 and a portion 45 of the shank 10 of the pin.

Secured near the upper, smaller diameter of the body 14, by rivets 16 or like fastenings, are a pair of rigid ornamental leaflike elements 17, which may be of any preferred 50 shape, a third leaf 18, of the same general

configuration, being spaced equally with the leaf members 17 around the body.

The leaf 18 is secured by a rivet 19, to a bracket-like element 20, fixed in the recess 20', formed at the side of the body, midway 55 in its length, the bracket 20 being pivoted on a pin 21, set transversely in the recess, and surrounding the pin 21 are the coils of a torsional spring 22, one end 23 of which is fixed in the body extending outwardly 60 from the recess, while the other end 24 is formed to exert pressure upon the inner side of the leaf element 18, holding its extending end 28 closely adjacent to the conical side of the body 14.

Attached by rivets 29, near the outer end of the element 28, is a projection 30, movable freely in a slot 31, formed near the smaller end, and engageable in an elongated slot 32, formed in the pin bar 10 so as to 70 secure the bar when engaged within the head.

The operation of removing the head or protector from the stem is merely to exert pressure upon the extending leaf 18, causing the same to pivot on the pin 21, the outer element 28 acting in the manner of a lever, withdrawing the projection 30 from the slot 32 thereby freeing the pin.

From the foregoing it will be seen that a 80 neat and effective protector for pins has been disclosed which may be easily operated and which prevents the point of the pin from interfering or damaging persons in the immediate vicinity and also maintain the 85 pin against loss.

Having thus described my invention what I claim as new and desire to secure by Letters Patent, is—

In a pin point protector the combination 90 with a pear-shaped body having a central axial bore and an upper and lower radial recess, a pin point enterable in said bore and having a longitudinal recess, a pair of leaf-like elements rigidly engaged with said body 95 near its smaller end, a transversely arranged pin in the lower recess of said body, a torsional spring coiled around said pin, a bracket pivoted to said pin, a third leaf-like element against which one end of said spring 100

is engaging, the other end of said spring embedded in said body, an extension secured to said third leaf, a projection attached to the upper end of said extension adapted to enter the upper of the recesses in said body and the slot of said pin point for normally securing the pin in said body but allowing

a ready attachment of the same from said body upon the pressure exerted on said third leaf.

In testimony whereof I have affixed my signature.

JOE SZCZUREK.
